UNITED STATES PATENT OFFICE.

FERDINAND MASSET, OF CHICAGO, ILLINOIS.

DESIGN FOR FURNITURE BACK FRAMES.

SPECIFICATION forming part of Design No. 14,912, dated March 25, 1884.

Application filed December 19, 1883. Term of patent 3½ years.

To all whom it may concern:

Be it known that I, FERDINAND MASSET, a citizen of the United States of America, residing at Chicago, in the county of Cook and State of Illinois, have invented certain new and useful Improvements in Designs for Furniture, of which the following is a specification, reference being had therein to the accompanying drawings.

10 My design relates to the backs of chairs, sofas, and like articles of furniture.

In the drawings accompanying this specification, and in which the design is clearly shown, Figure 1 represents a front elevation of the back of a sofa or chair, and Fig. 2 a section on line 1 1 of Fig. 1.

In these drawings, A represents the top rail of the back, which is ornamented as shown.

15 B B are the end uprights, which connect the top rail with the seat; and C, a central support provided with suitable ornamentation, as shown in Fig. 1.

D represents a piece mounted upon the top rail, A, at about the center thereof. This piece 20 D, which is the principal feature in the design, is provided with suitable ornamentation corre-

sponding with that of other parts of the frame. This piece D is rectangular in shape, and rests directly upon the top rail of the frame, to all appearance forming a part thereof. 30

I am aware that heretofore sofas, settees, &c., have been provided with a top piece provided with an ornamented center, and with extending arms, which rest at their outer ends upon the top rails of the article, and also that 35 towel-racks have been provided with ornamental arches connecting the upright supports thereof; but I disclaim these configurations.

What I claim is— 40

In a design for furniture back frames, the top rail, A, provided with ornamented piece D, rectangular in shape, and resting directly upon said top rail, end uprights, B B, and central ornamented upright or support, C, as shown 45 in the accompanying drawings.

In testimony whereof I affix my signature in presence of two witnesses.

FERDINAND MASSET.
